UNITED STATES PATENT OFFICE.

NICOLAUS KAUTEN, OF CHICAGO, ILLINOIS.

NON-REFILLABLE BOTTLE.

No. 833,395.

Specification of Letters Patent.

Patented Oct. 16, 1906.

Application filed May 26, 1905. Serial No. 262,321.

To all whom it may concern:

Be it known that I, NICOLAUS KAUTEN, a subject of the Emperor of Austria-Hungary, residing at Chicago, in the county of 5 Cook and State of Illinois, have invented new and useful Improvements in Non-Refillable Bottles, of which the following is a specification.

My invention relates to non-refillable bottles; and the object of my invention is to provide a bottle or other liquid-receptacle which cannot be refilled after its original contents have been removed.

Furthermore, the object of the invention 15 is to provide an attachment adapted to be applied to the neck of a bottle after the latter has been filled which will only permit the free outward passage of the liquid.

Finally, the object of the invention is to 20 provide an attachment having springs secured thereto and adapted to seat in an annular recess in the neck of the bottle, thereby preventing the removal of the device after being inserted in the neck of the bottle.

With the foregoing and other objects in 25 view the invention consists in the details of construction and in the arrangement and combination of parts to be hereinafter fully described and the novel features particularly 30 pointed out in the claims.

In describing the invention in detail reference will be had to the accompanying drawings, forming a part of this specification, wherein like characters denote corresponding parts in the several views, and in 35 which—

Figure 1 is a vertical sectional view 40 through the neck of a bottle, showing a bottle and stopper therefor constructed in accordance with my invention. Fig. 2 is a perspective view of the stopper. Fig. 3 is an end view of the stopper, and Fig. 4 is a detail view of the spiral guard.

Bottles to which my invention is adapted 45 to be applied are not essentially different from those in use, but are preferably provided with a neck 1, having the straight internal bore and provided intermediate its length with an annular recess 2 and at the 50 lower end of the neck with a shoulder 3, the functions of which will hereinafter be fully described.

The attachment or stopper is adapted to 55 be inserted in the neck of the bottle, and consists of a tube 4, which is provided with cork, wood, or rubber collars 5 and 6, said collars

being secured at each end on the outer peripheral surface of the tube. A metal ring 7, which is provided with a bevel edge 8, is secured within one end of the tube 4, said 60 ring forming a valve-seat for a ball-valve 9. Arranged above the ball-valve is a spiral-shaped guard 10, which is connected at one end to the upper or opposite end of the tube from the valve-seat and extends in the tube 65 to within a short distance of the ball-valve. The spiral guard 10 forms an indirect passage to the valve and effectually preventing the insertion of any instrument, whereby the valve might be held off its seat and at the 70 same time afford a free passage for the liquid.

In order to permit a free passage of the liquid from the bottle, I provide the space between the spiral guard and ball-valve, whereby the ball is permitted to move away 75 from its seat to permit the free egress of the liquid when the bottle is inverted or turned on its side.

The device is provided with spring-catches 80 11 and 12, which engage in the annular recess of the neck, thereby preventing the withdrawal of the device.

In operation the bottle is first filled with the desired liquid and the device is inserted in the neck of the bottle until the end of the 85 tube seats against the shoulder 3, and the ends of the springs will then be in a line with the annular recess of the neck, and at the same time the ends of the springs will seat in the recess, and thereby lock the device in 90 order to prevent its removal from the neck of the bottle. After the device is secured in place a stopper 13 is inserted in the end of the neck of the bottle to prevent dust or dirt from accumulating in the device. 95

The construction, operation, and advantages will, it is thought, be understood from the foregoing description, it being noted that various changes may be made in the proportions and details of construction for carrying 100 the invention into practice without departing from the scope of the invention.

Having fully described my invention, what I claim as new, and desire to secure by Letters Patent, is—

1. The combination with a bottle of a tube provided with a collar at each end secured on the outer peripheral surface of the tube and a valve-seat secured within one end of the tube, a ball-valve adapted to seat within the tube 110 and a spiral guard suitably secured at one end and extending inwardly of the tube and

spring-actuated means for preventing the removal of the tube from the neck of a bottle.

2. The combination of a tube provided with a valve-seat at one end and a spiral guard having one end secured to the inner surface of the tube and extending a predetermined distance within the tube and spring-actuated means for preventing the removal of the tube from the neck of a bottle as and 10 for the purpose described.

3. In combination with a bottle-neck having an annular recess intermediate its length and provided with an annular shoulder at one end, a tube provided with a collar on its 15 peripheral end surfaces and with a ring secured within one end, said ring providing a valve-seat, a ball-valve adapted to seat on the ring and a spiral guard secured in the tube directly over the ball-valve substantially as described.

4. In a device of the character described, a tube provided with collars on its peripheral end surfaces, springs secured to the tube, a ring-valve seat secured within one end of the 25 tube, a ball-valve adapted to seat on said

ring-valve seat, a spiral guard having one end secured to the end of the tube and extending a predetermined distance within the tube, and spring-actuated means for locking the tube within the neck of a bottle as and 30 for the purpose described.

5. In combination with a bottle-neck provided with an annular recess intermediate its length and having a shoulder at one end, a tube provided with a collar on each end 35 and a beveled ring-valve seat secured within one end of the tube and a spiral guard secured within the opposite end of said tube, said spiral guard extending within the tube a predetermined distance, and springs secured on 40 the outer surface of the tube and adapted to engage in the annular recess of the neck.

In testimony whereof I have affixed my signature in presence of two subscribing witnesses.

NICOLAUS KAUTEN.
